UNITED STATES PATENT OFFICE

HENRY CAVE, OF HARTFORD, CONNECTICUT, ASSIGNOR TO THE FULLER BRUSH COMPANY, OF HARTFORD, CONNECTICUT, A CORPORATION OF CONNECTICUT

BRACE FOR BROOM HANDLES

Application filed December 13, 1927. Serial No. 239,736.

My invention relates particularly to means for attaching a broom handle to a broom head, and especially when the handle is removable, and an object of my invention, 5 among others, is the provision of means whereby such handle may be rigidly and securely attached in position.

One form of a broom embodying my invention, and in the construction and use of 10 which the objects herein set out, as well as others, may be attained, is illustrated in the accompanying drawings, in which—

Figure 1 is a top view of a broom embodying my invention, the outer portion of 15 the handle being broken off.

Figure 2 is a front view of the structure.

Figure 3 is an end view, and

Figure 4 is a view in central crosswise section.

20 In the accompanying drawings the numeral 5 indicates a broomhead to the under side of which bristles 6 are secured in any suitable manner. It is common practice at the present time to construct this head of 25 wood or similar material which is of suitable thickness, the handle 7 being removably secured to the head as by means of a screw-threaded, preferably tapered, end 8 fitting a hole similarly formed in the head. Frequently two holes are made in the head located at an angle to each other so that the 30 handle may be attached for use on either side of the broom as may be desired.

It has been found in practice that the 35 handle readily becomes loosened and, moreover, the screw-threaded tip is liable to be broken off or the broom head to be split, especially when the handle becomes loose so that some play is permitted in its socket in said head. To avoid these results, I have 40 provided means to enable the handle to be very securely and rigidly attached to the head, such means comprising a brace formed of comparatively heavy wire.

45 This brace is of substantially U-shape, comprising arms 9 oppositely arranged and joined at their upper ends by a yoke 10. This yoke is located at one side of the plane 50 of the arms 9 and is curved to fit the handle 7, which is generally round in cross section.

The arms 9 at their upper ends extend preferably in a plane passing substantially through the axis of the handle, but at their lower ends said arms are bent out of this plane, as clearly shown in Fig. 3, and the 55 lower ends are formed with lips 11 extending under and in close contact with the under surface of the head 5, and as shown in Fig. 4 of the drawings. The formation of these lips provides grooves 12 in which the corner 60 of the head is located.

The member just described and comprising the branching arms 9 is supported and secured in place by means of a tie 13 with loops 14 at its opposite ends to receive the 65 arms, this tie extending over the handle in opposition to the yoke 10, said yoke and tie in fact constituting a hole, when the brace is viewed from the end, through which the 70 handle 7 extends. The loops 14 are closed tightly around the branches 9, and said tie and yoke are formed to so tightly embrace the handle as to prevent any looseness between the handle and the brace as a whole, so that the handle is very rigidly and firmly 75 held in position. This grip of the brace upon the handle, however, will not be such that the handle cannot be rotated when sufficient power is applied to it to remove it from the head, but this grip will preferably be 80 such that more power will be required to turn the handle than is commonly applied to it in the ordinary uses to which the broom is subjected.

While my improved brace has been shown 85 herein as used with a handle screw-threadedly engaged with the broom head I do not wish to be understood as limiting my invention to such use, as it is equally applicable to other means for securing the handle, as for instance, one in which a smooth handle end is secured in an unthreaded hole.

In accordance with the provisions of the 90 patent statutes I have described the principles of operation of my invention together with the device which I now consider to represent the best embodiment thereof; but I desire to have it understood that the device shown is only illustrative and that the invention may be carried out by other means 95 100.

and applied to uses other than those above set out.

I claim—

- 5 1. In combination with a broom head and a handle having its end extended into a hole in said head, a brace comprising branching arms connected by a yoke at one end and removably engaged with said head at their opposite ends, said yoke extending partially around said handle, and a strand of wire 10 forming a tie secured at its ends by loops to said branches and passing around the opposite side of the handle from said yoke.
- 15 2. In combination with a broom head and a handle having its end extended into a hole in said head, a brace comprising branching arms connected by a yoke at one end, lips at the opposite ends of said arms engaging the under surface of the broom head and 20 forming a groove to receive the corner of said head, said yoke extending partially around said handle, and a strand of wire forming a tie secured at its ends by loops tightly encircling said branches and passing 25 around the opposite side of the handle from said yoke, said yoke and tie being formed to tightly grip said handle.

HENRY CAVE.
